(57) **CLAIM**

We claim the ornamental design for a vehicle side nerf bar, as shown and described.

DESCRIPTION

FIG. 1 is an upper, left, front perspective view of a vehicle side nerf bar;

FIG. 2 is left side elevation view thereof;

FIG. 3 is a right side elevation view thereof;

FIG. 4 is a rear elevation view thereof;

FIG. 5 is a front elevation view thereof;

FIG. 6 is a top plan view thereof;

FIG. 7 is a bottom plan view thereof;

FIG. 8 is a lower, right, rear perspective view thereof;

FIG. 9 is an upper, right, rear perspective view thereof; and, FIG. 10 is an upper, left, front perspective environmental use view of the vehicle side nerf bar.

In the drawings, the broken line showing of features of a vehicle side nerf bar illustrate portions of the vehicle side nerf bar that form no part of the claimed design; whereas, the broken line showing of the environmental use view depicts environmental subject matter and is provided for the purposes of illustrating environmental use structure and context and also forms no part of the claimed design.

In the drawings the left side of the vehicle side nerf bar is being shown, the right side is a mirror image thereof.
